DESIGN FOR A CIGARETTE DISPENSER

Daniel Volpe, New York, N. Y.

Application September 19, 1946, Serial No. 133,414

Term of patent 3½ years

(Cl. D85—2)

To all whom it may concern:

Be it known that I, Daniel Volpe, a citizen of the United States of America, and a resident of the city of New York, in the county of Bronx and State of New York, have invented a new, original, and ornamental Design for a Cigarette Dispenser, of which the following is a specification, reference being had to the accompanying drawing, forming a part thereof.

Figure 1 is a front elevational view of a cigarette dispenser, showing my design;

Fig. 2 is a side view thereof;

Fig. 3 is a top view thereof; and

Fig. 4 is a rear view thereof.

I claim:

The ornamental design for a cigarette dispenser, substantially as shown.

DANIEL VOLPE.
